UNITED STATES PATENT OFFICE

2,557,527

IGNITION SYSTEM FOR INTERNAL-COMBUSTION ENGINES

Clifford Colvin, Detroit, and Eugene C. Bettini,
Bloomfield Hills, Mich., assignors to George M.
Holley and Earl Holley

Application September 23, 1948, Serial No. 50,796

1 Claim. (Cl. 123—117)

1

The object of this invention is to advance and to promptly retard the spark of an automobile engine as circumstances require, specifically to advance:

(a) When the speed increases at wide open throttle.

(b) When the throttle is opened and the engine runs slowly.

(c) To retard the spark to its non-knocking position very quickly when the throttle is opened quickly at low engine speed. (To avoid the well known acceleration "knock.")

The figure shows the preferred form of our invention.

In the figure, 10 is the air entrance of a conventional carburetor 12. 14 is the fuel nozzle discharging into the venturi 16 in the air entrance of the main air passage 17. (There is a low speed fuel outlet discharging into the mixture outlet 19 and discharging adjacent the upstream lip of the butterfly throttle 32.) 18 is a small passage leading out of the throat of the venturi 16 into a chamber 20. 22 is the first moving wall or diaphragm forming the left hand wall of chamber 20. 24 is a second moving wall or diaphragm forming the left hand wall of a chamber 26 which is connected through a pipe 28 with an opening 30 in the main air passage 17, located just above the atmospheric side of the lip of the carburetor throttle 32 when the carburetor throttle 32 is in its idle position.

A spark control rod 34 engages with plate 44 and is moved by two means:

(a) Directly by the diaphragm 22 to which it is connected positively, and

(b) Indirectly by a sleeve or tube 36 surrounding the rod 34.

This sleeve 36 is slotted so that it can pull the right hand end 38 of the rod 34 to the left but the rod 34 is free to be moved to the left by springs 46, 47 and plate 44, even though the tube 36 remains in the position shown. In other words the end of the rod 34, numbered 38, has a one way connection which projects through a slot in the sleeve 36, and engages with the circuit breaker plate 44. The tube 36 has a rod extension 40 which is engaged by a compression spring 42. The spring 42 engages with a stationary abutment on the left and with an adjustable lock-nut 43 threaded onto the rod 40 and forming the movable abutment on the right for the spring 42. The adjustment of nut 43 regulates part throttle spark advance. This spring is designed to cause a rapid movement to the right of the sleeve 36 so as to permit the rapid rotation of the

plate 44 (clockwise) to retard the spark whenever the throttle is quickly opened, even if it is not opened completely. The absence of restrictions in the pipes 18 and 28 ensures the rapid retardation of the spark.

The plate 44 is pulled clockwise by two springs 46 and 47, one of which is initially tight, the other one is loose. These three springs 42—46—47 control the position of the plate 44 at all times. The reason one of the two springs 46—47 is loose is that one thus tightens up before the other. (See Westcott et al. case, filed December 20, 1946, Serial No. 717,536, now Patent No. 2,503,645, issued April 11, 1950.) The plate 44 carries a circuit breaker arm 48 which engages with a stationary contact 49. The circuit breaker arm 48 is opened and closed by a cam 50, a finger 53, and a spring 52. An electrical connection 54 is provided for the low tension side of the coil (not shown).

The spring anchor pins 56—57 project through circular openings in the circuit breaker plate 44 to provide a maximum but limited advance of the spark determined by the clearance of the pins 56 and 57 in these openings.

Operation

If running normally (approximately 7 pounds per square inch) suction is applied to the second moving wall 24 and the spring 42 is set to be overcome by this suction at any suction greater than say 1 1/4 pounds per square inch. The diaphragm 24 is held in the position shown when the throttle 32 is suddenly opened somewhat beyond the position shown in broken lines. The suction in the mixture outlet 19 in that case drops. Instantly the spring 42 removes the load on the rod end 38, imposed by the second moving wall 24 which held the spark advanced, and as the suction in venturi 16 is still feeble the two springs 46—47 quickly restore the spark to a relatively retarded position, that is, to a "non-knocking" position.

By this means the spark advance is ruled at all times by the venturi suction except when the suction in the mixture outlet 19 exceeds the force required to overcome compression spring 42, that is, above about 1 1/4 pounds per square inch suction.

The angle from rod end 38 to the center of cam 50 is just under 90° and as the spark is advanced this angle goes just over 90°. Hence, the slot in the tube 36 need not be made much wider than the pin 38 to permit the necessary movement.

What we claim is:

An internal combustion engine ignition system, a main air passage, a throttle therein and a main air entrance therefor, a streamlined restriction in said entrance, a first chamber, a first moving wall therein, a passage from the chamber to the air entrance at said restriction so that the moving wall responds to the pressure drop at said restriction due to air flow, a second chamber, a second moving wall therein, said second chamber being connected to the main air passage at its outlet on the engine side of the throttle when the throttle is first moved from its idling position so that said second moving wall responds to engine suction at part throttle, a spark timing advance plate including a circuit breaker mechanism, a first spring engaging said plate so as to hold it in its spark retarded position whenever the engine is not running, a second control spring for said second moving wall, a first rod connecting the first moving wall with said plate, a second rod connecting the second moving wall with said plate including a one way connection between the second rod and said plate so that the plate can be advanced by the first moving wall although the second moving wall is held back by its second control spring, said second control spring having a stiffness such that normal engine suction causes it to yield so as to permit the second moving wall to advance the spark in response to engine suction downstream from said throttle

when the engine is running at any normal speed and the throttle is set for normal road load, in which one end of the second rod is slotted to permit one end of the first rod to project through said slot to engage the plate, the other end of the said second slotted rod continuing as a rod which rod is engaged by said second control spring and is threaded and provided with an adjustable abutment to vary the strength of the engine suction at which the second rod engages with the spark advance circuit breaker plate.
